UNITED STATES PATENT OFFICE.

LEOPOLD JOSEPH ATKINSON, OF WANGANUI, NEW ZEALAND, ASSIGNOR TO GIBSONS & PATERSON, LIMITED, OF WELLINGTON, NEW ZEALAND, A LIMITED JOINT STOCK COMPANY OF NEW ZEALAND.

DOOR OR GATE FASTENING.

Application filed April 21, 1922. Serial No. 555,878.

The invention relates to door or gate fastenings, and more particularly to novel devices or mechanisms of the kind described having the special characteristics herein-
5 after defined and pointed out.

Objects and advantages of the invention will be set forth in part hereinafter and in part will be obvious herefrom, or may be learned by practice with the invention,
10 the same being realized and attained by means of the instrumentalities and combinations pointed out in the appended claims.

The invention consists in the novel parts, constructions, arrangements, combinations
15 and improvements herein shown and described.

The accompanying drawings, referred to herein and constituting a part hereof, illustrate one embodiment of the invention,
20 and together with the description, serve to explain the principles of the invention.

Of the drawings:—

Fig. 1 is an isometric perspective of a door or gate fastening embodying the invention;
25

Fig. 2 is a side elevation looking at Fig. 1 from the left;

Fig. 3 is a fragmentary perspective, similar to Fig. 1, and showing a padlock
30 applied to the door fastening; and

Fig. 4 is an elevation of a door with the fastening applied thereto.

Fig. 5 is an isometric perspective taken from the opposite side from Fig. 1; and
35

Fig. 6 is a central vertical section, with parts in elevation, looking from the opposite side from Fig. 2.

Referring in detail to the embodiment of the invention illustrated by way of example in the accompanying drawings, the device is shown embodying a base plate 1, provided with suitable means for attachment to a door or gate 2, such as screws 3 and 4, which may be upset on the inside of the structure, as shown in Fig. 2, or which may be locked or anchored into the structure in any other suitable manner. As embodied, the base plate 1 terminates at either end in outwardly extending ears 5 and 6, in which the latching member is journaled, and the ears are apertured at or near their centers for this purpose.

The present preferred form of latching device comprises a swinging member with

an ample hand grip, such as the hand bail 55 or latch 7, which is formed preferably of a metal rod. The bail as embodied has a central hand grip 8, which may be a straight part of the rod, which is of greater length than the distance between the ears 5 and 6, whereby it projects beyond the edge of the door, to engage with the catch which is supported on the building wall or equivalent part or structure. At the outside end of the grip 8 of the bail or latch 7, the rod 60 is bent inwardly toward both the base 1 and the ear of the base plate (and this may be done at the other end also), as shown at 9 and 10. The ends of said inwardly bent portions 9 and 10 pass through the 65 ears 5 and 6, and preferably are bent on the inside, as shown at 11, to retain the bail latch journaled in the ears 5 and 6.

The end 11^a of the bail is preferably bent downwardly, as shown in Fig. 6, so that it 70 strikes plate 1 and acts as a stop when the bail 7 lies at rest. The opposite end of the bail 7 is preferably bent upwardly, as shown in dotted lines in Fig. 6, and acts as a stop to limit the upward movement of the bail 75 80 by striking against plate 1. These parts are preferably so proportioned, that when the part 12 of the bail 7 strikes the detent 16, the rising or upward movement of the bail is arrested by the end 11 striking plate 85 1, which snaps the bail or latch 7 into the catch or detent 16. Lug 11 by striking plate 1 immediately after bail 12 has struck 90 16 causes 12 to rebound into the catch at 17, and requires no manual pressure to snap it down into its seat. Thus the bail latches automatically by the mere closing of the door.

The outwardly extending end 12 of the bail latch in the construction just described 95 constitutes the part of the device which engages with the catch or detent on the jamb or side post 13, as will clearly appear from the drawings.

The catch 16 is preferably constructed 100 and arranged to hold the member 7 firmly against displacement except when it is lifted by the hand of a person wishing to open the door or gate. For this purpose the detent 16 is shaped to have a holding surface 105 or part 17, formed straight as shown in Fig. 3 or concaved as shown in Fig. 2 so that the bail latch 7 will snap down under man-

ual pressure, or will drop by gravity, into a seat therewithin, and will remain securely in its seat until lifted by manual pressure in the opposite direction. This may be effected by the natural spring in the door or gate and the catch may be solid or non-yielding, or if desired, the catch 16 may be made to have the desired degree of resili-
ent action. The angle of inclination of the bail or handle 7 is such as to directly resist an opening pressure on the door, such pres-
sure tending to press the handle 7 more firmly in position within the catch. The latch 16 is fastened to the frame or jamb
13 in any suitable manner, and as shown screws 18 and 19 are employed having their inner ends upset as shown in Fig. 2.

The construction is such that a great deal of closing pressure may be utilized for the door, as the firm and roomy hand grip pro-
vided by the part 7 enables practically any desired amount of force to be manually em-
ployed in both the closing and opening movements.

25 In Fig. 3 a padlock 24 is shown passing through openings 25 in the catch or detent 16 and over the bail latch 7, thereby locking the device securely in position.

30 In Fig. 4 the application of the lock to a door 26 is shown, the door being swung on hinges 27 and 28 attached to the building wall 29.

35 It will be understood that changes may be made in the details of construction from the present preferred showing, within the scope of the accompanying claims, without de-
parting from the invention or sacrificing its chief advantages.

What I claim is:-

40 1. A door or gate fastening including in combination a bail, means for mounting it to swing on the outer face of a door or gate, the bail having a portion thereof extending outwardly beyond the door or gate, a catch
45 on the wall adjacent the door or gate, said projecting part of the bail engaging within the catch to hold the door or gate in closed position with the front surface of the door or gate flush with said wall and a padlock passing through the bail and the catch.

50 2. A door or gate fastening comprising a

bail, means for pivotally mounting the bail on the outer face of the door or gate so that it swings about an axis substantially parallel to the door or gate, and a catch secured on the wall adjacent the door or gate for engagement with the bail for holding the door or gate closed flush with said wall.

55 3. A door or gate fastening comprising a bail, means for pivotally mounting the bail on the outer face of the door or gate so that it swings outwardly therefrom and extends beyond one edge thereof, and a catch se-
cured on the wall adjacent the door or gate in which the bail rests by gravity for en-
gagement with said extending part of the bail for holding the door or gate flush with said wall.

60 4. A door or gate fastening comprising a bail, means for pivotally mounting the bail on the outer face of the door or gate so that it swings about an axis substantially parallel thereto with one end extending be-
yond one edge thereof, and a resilient catch secured on the wall adjacent the door or
gate into which the extending end of the bail snaps for holding the door or gate closed for holding the door or gate flush with said wall.

65 5. A door or gate fastening comprising a plate secured to the outer face of the door or gate and provided with outwardly ex-
tending ears, a handle element pivotally carried by the ears and extending beyond the edge of the door or gate and a catch secured on the wall adjacent the gate for engaging one end of the handle element.

70 6. A door or gate fastening comprising a bail provided with looped ends, means for pivotally mounting the bail on the outer face of the door or gate so that it turns about an axis substantially parallel thereto and has one of its looped ends extending be-
yond the edge of the door or gate, a catch secured on the wall adjacent the door or
gate with which one of the looped ends en-
gages for holding the door or gate flush with said wall, and a padlock engageable with said looped end and with the catch.

75 In testimony whereof, I have signed my name to this specification.

LEOPOLD JOSEPH ATKINSON.
